UNITED STATES PATENT OFFICE.

ALFRED J. STECKER, OF DETROIT, MICHIGAN, ASSIGNOR TO FRED WARDELL, OF DETROIT, MICHIGAN.

HANDLE DEVICE FOR VACUUM-CLEANERS.

1,231,445.

Specification of Letters Patent.

Patented June 26, 1917.

Application filed August 26, 1916. Serial No. 117,001.

To all whom it may concern:

Be it known that I, ALFRED J. STECKER, a citizen of the United States of America, residing at Detroit, in the county of Wayne 5 and State of Michigan, have invented certain new and useful Improvements in Handle Devices for Vacuum-Cleaners, of which the following is a specification, reference being had therein to the accompanying 10 drawings.

The invention relates to vacuum cleaners and relates particularly to portable vacuum cleaners such as are commonly provided with swinging handles.

15 It is desirable under certain conditions to retain the swinging handle of a portable vacuum cleaner either in substantially vertical or a substantially horizontal position, the former position being desirable when 20 the appliance is not in use and the latter position being convenient when it is desired to use the appliance in a raised position as for cleaning mattresses or stair treads.

The object of the invention is broadly to 25 provide means for yieldably retaining a pivoted handle of a vacuum cleaner in a certain position of adjustment relative to the unit.

A more specific object of the invention is 30 to provide a common means for yieldably retaining the pivoted handle of a vacuum cleaner either in a substantially vertical or substantially horizontal position.

In the drawings:

35 Figure 1 is a perspective view of a vacuum cleaner employing my improvement, the handle being shown retained upright;

Fig. 2 is a view in side elevation and partial section, the handle being shown in substantially horizontal position;

Fig. 3 is a detail front elevation view showing the device employed to retain the handle upright.

In these views the reference characters 1, 45 2 and 3 respectively designate the motor casing, fan casing and suction inlet of a vacuum cleaner. The handle 4 thereof is connected to the body of the vacuum cleaner by a bifurcated bracket, the furcations 5 of which straddle the motor casing and are pivoted thereto at diametrically opposite points. To connect said bracket to the handle proper, there is employed a member, the upper portion 6 of which forms a socket receiving the handle, and the lower

portion 7 of which is of rectangular form and is engaged between the upper ends of the furcations 5 by any suitable securing means. Upon the parts 6 and 7 there are respectively formed bosses 8 to which is secured a channel shaped guide 9 by means of screws 10, said guide extending parallel with the handle. At its end closest adjacent the motor casing the bottom of the guide 9 is formed with an aperture 11 into which projects a curved portion 12 of a spring 13, said spring being disposed between the guide 9 and the member 7 and being retained in place by engagement of one of its extremities between said guide and one 60 of the bosses 8. The sides of the guide are formed with inwardly projecting flanges 14, beneath which flanges are engaged the extremities of a pin 15 adapted to be displaced longitudinally of the guide. Said pin is 65 carried by one extremity of a curved swinging link 16, said extremity being formed with a sleeve 17 to engage the pin. Preferably the link will be reduced slightly in width adjacent the sleeve 17 so as to permit 70 of its passage between the flanges 14. At its other extremity the link 16 is pivotally mounted upon the rear end of the motor as indicated at 18.

When the handle is in either a substantially vertical or a substantially horizontal position, the pin 15 is at the end of the guide 9 nearest adjacent the motor casing, as is shown in the drawing, and the spring 13 presses its curved portion 12 through the 85 aperture 11 and against the sleeve 17 thus acting to yieldably retain said pin in the described position. When the handle is swung either upwardly or downwardly, the link 16 is subjected to a stress whereby the 90 portion 12 of the spring 13 is forced out of the guide allowing the end of the link carrying the pin 15 to slide toward the rear end of the guide. The rearmost position of 95 said pin relative to the guide is reached 100 when the handle is shifted to a position substantially midway between those illustrated in Figs. 1 and 2. By virtue of the curvature of the link 16 it may swing freely between its two limiting positions without 105 obstruction of its position by the motor casing.

What I claim as my invention is:

1. The combination with a portable appliance, of a handle pivoted thereupon, a link 110

connecting said appliance and handle having a pivotal engagement with one of said members and sliding engagement with the other, and a common means for yieldably retaining 5 said link against motion in a plurality of positions of the handle relative to the appliance.

2. The combination with a portable appliance, of a handle pivoted thereupon, a 10 link connecting said appliance and handle having pivotal engagement with one of said members and sliding engagement with the other, a channeled guide carried by the latter named member engaged with said link, 15 the bottom of said guide being apertured, and a spring mounted exteriorly to said guide having a portion projecting through the aperture thereof and engageable with the link to yieldably hold the same against 20 motion in a certain relative position of the handle and appliance.

3. The combination with a portable appliance, of a handle pivoted thereupon, a channeled guide carried by the handle having 25 its sides formed with inwardly projecting flanges, a pin having its extremities engaged beneath said flanges, said pin being 30 slidably longitudinally of said guide, a link carrying said pin at one extremity and pivoted upon said appliance at its other extremity and means associated with one extremity of said guide for yieldably retaining the pin carrying end of the link at said extremity when the handle occupies a certain 35 pivotal position relative to the appliance.

4. The combination with a portable appliance, of a handle pivoted thereupon, a link connecting said appliance and handle having one of its extremities pivotally engaged with one of said members and slidably engaged with the other member, a guide carried by the latter member engaging the sliding end of said link and a latch member carried by said guide engageable 40 with the sliding end of the link in a plurality of positions of the handle and establishing the handle in a rigid relation with the appliance in said positions, said latch 45

member being yieldable under the application of sufficient force to the handle. 50

5. The combination with a portable appliance, of a handle pivoted thereupon, a link having one of its extremities pivotally engaged with said appliance, a guide member carried by the handle and guiding the other extremity of the link in a sliding motion when the handle is angularly displaced, the relative positions of the guide member and link extremity engaged thereby being substantially the same when the handle occupies either a definite raised or definite lowered position, and means carried by the guide engaging the sliding end of the link in said positions of the handle and yieldably resisting displacement of the 60 sliding link extremity in said guide. 65

6. The combination with a portable appliance, of a handle pivoted thereupon, a link having one of its extremities pivotally engaged with one of said members and its other extremity slidably engaged with the other member, the relative positions of the sliding link extremity and the member engaged thereby being substantially the same when the handle occupies either a definite 70 raised or definite lowered position, and means engaging the sliding end of the link in said definite positions of the handle and resisting displacement thereof. 75

7. The combination with a portable appliance, of a handle pivoted thereupon, a channeled guide carried by one of said members having its sides formed with inwardly projecting flanges, a pin having its extremities engaged beneath said flanges, said pin 80 being slidably longitudinally of said guide, a link carrying said pin at one extremity and pivoted upon the other of said members at its other extremity, and means associated with one extremity of said guide for yieldably retaining the pin carrying end of the link at said extremity when the handle occupies a certain pivotal position relative to the appliance. 85

In testimony whereof I affix my signature. 90
ALFRED J. STECKER. 95
